UNITED STATES PATENT OFFICE.

FRANCIS H. TREAT, OF PITTSBURG, PENNSYLVANIA.

REGENERATIVE FURNACE.

SPECIFICATION forming part of Letters Patent No. 705,978, dated July 29, 1902.

Application filed November 14, 1901. Serial No. 82,218. (No model.)

To all whom it may concern:

Be it known that I, FRANCIS H. TREAT, of Pittsburg, Allegheny county, Pennsylvania, have invented a new and useful Regenerative Furnace, of which the following is a full, clear, and exact description, reference being had to the accompanying drawings, forming part of this specification, in which—

Figure 1 is a plan view of a series of three regenerative pit-furnaces in horizontal section on the lines X X, Y Y, and Z Z of Fig. 3 constructed in accordance with my invention. Fig. 2 is a perspective view of the air-flues, the walls of the furnace being broken away. Fig. 3 is a cross-section on the line III III of Fig. 1.

My invention relates to that class of furnaces wherein single-surface regenerators are used and is designed to arrange the regenerative flues and checker-work in compact form, so that a series of furnaces with their regenerators may be placed side by side, each furnace being independent of the others.

Heretofore in the class of pit-furnaces a series of furnaces have been combined with a single set of regenerators, and it has been found difficult to keep the different furnaces at the proper heat, some of the furnaces working too cold and others too hot. My invention overcomes this difficulty by combining with each furnace a self-contained regenerative system.

In the drawings, in which I show a preferred form of the invention, 2 represents a pit-furnace having at each end a gas-regenerative chamber 3 and an outer air-regenerative chamber 4. The air-regenerator on the air side is provided with a flue 5, leading outwardly and thence upwardly into a valve-casing 6. Within this casing is a reversing butterfly-valve 7, which controls a central flue 8, leading downwardly to the chimney-flue 9, and outside of flue 8 is a flue 10, which in its lower portion extends laterally and thence downwardly and extends beneath the furnace to the air-regenerator upon the opposite side of the furnace. The air-valve casing is provided with a valve 11 in its open top, which controls the supply of air flowing into the casing.

The gas-valve casing 12 is similar to that of the air-valve, but is inclosed in a gas-box

13, to which the gas-supply pipe leads. The reversing-valve 14 and the gas-valve casing are similar to the other reversing-valve and control a gas-port 15, leading downwardly and horizontally under the furnace and opening into the opposite gas-regenerator. The central flue 16 on the gas side leads to a chimney-flue 17, and the rear flue 18 is offset laterally and thence extends downwardly and enters the lower portion of the gas-regenerator on the same side of the furnace.

In the operation of the furnace when the valves are in the position shown in Fig. 3 gas passes into the gas-valve casing and is directed into the rear gas-flue, whence it passes into the gas-regenerator on the same side of the furnace. At the same time air enters the air-valve casing on the opposite side of the furnace, enters the outside flue therein, passes down beneath the furnace and into the air-regenerator on the gas side, as shown in Fig. 1 by the arrows. The air and gas passing up through the two regenerators on the gas side are ignited in the usual manner, and the products of combustion pass through the furnace and down through the air and gas regenerators on the air side. That portion of the products passing down through the air-regenerator flows on into the air-valve casing and thence down into the chimney-flue, while the products passing down through the gas-regenerator flow into the flue extending beneath the furnace, thence upwardly into the gas-valve casing, and downwardly to the other chimney-flue. When the air and gas valves are reversed, air flows into the air-valve casing and thence directly into the air-regenerator on the same side. At the same time gas flows in through the gas-valve casing and passes to the inner flue and thence down under the furnace and up into the gas-regenerator on the air side. The products of combustion in this case pass into the gas and air regenerators on the gas side, and that portion entering the air-regenerator passes from this regenerator beneath the furnace and up into the outer flue in the air-valve casing and thence to the chimney-flue, while the products of combustion passing through the gas-regenerator flow from this regenerator upwardly into the outer part of the gas-valve casing and thence to the chimney-flue on the gas side.

The advantages of my invention result from the peculiar arrangement of the regenerative flues. This system of flues gives a compactness which enables each furnace to be provided with its own regenerative system, while allowing the furnaces to be placed side by side and extended in a line to any desired number.

Many variations may be made in the form and arrangement of the furnace, the regenerators, the system of flues, and the valves without departing from my invention as claimed.

I claim—

15 1. A regenerative furnace having air and gas regenerators on each side thereof, reversing-valves on opposite sides of the furnace, and a flue leading from one regenerator on each side to the reversing-valve on the side opposite the said regenerator; substantially as described.

20 2. A regenerative furnace having gas and air regenerators arranged in pairs on each side thereof, a reversing air-valve on one side, a reversing gas-valve on the other side, one of each pair of regenerators having a flue leading beneath the furnace to the valve on the other side thereof, while the other of said pair has a flue connection to the valve on the same side; substantially as described.

25 3. A regenerative furnace having gas and air regenerators arranged in pairs on each

side thereof, an air-valve casing on one side having three flues, one leading to the chimney-flue, another to the air-regenerator on the same side of the furnace, and the third leading to the air-regenerator on the opposite side of the furnace, and a gas-valve casing having three flues, one leading to the gas-regenerator on the same side, one to the chimney-flue, and the third to the gas-regenerator on the opposite side, and reversing-valves within the valve-casings; substantially as described.

40 4. A regenerative furnace having a pair of regenerators on each side thereof, one of each pair being a gas-regenerator and the other an air-regenerator, three flues on one side of the furnace, one leading to the chimney-flue, another to the air-regenerator on the same side, and the third to the air-regenerator on the opposite side, three flues on the other side of the furnace, one a chimney-flue, the second leading to the gas-regenerator on the same side, and the third leading to the gas-regenerator on the opposite side, and valve mechanism for reversing the flow to the regenerators; substantially as described.

45 In testimony whereof I have hereunto set my hand.

FRANCIS H. TREAT.
